UNITED STATES PATENT OFFICE.

FRANK C. RINSCHE, OF ST. LOUIS, MISSOURI, ASSIGNOR TO UNIVERSAL ACCOUNTANT MACHINE COMPANY, OF ST. LOUIS, MISSOURI, A CORPORATION OF MISSOURI.

CALCULATING-MACHINE.

SPECIFICATION forming part of Letters Patent No. 726,803, dated April 28, 1903.

Application filed May 9, 1901. Serial No. 59,391. (No model.)

To all whom it may concern:

Be it known that I, FRANK C. RINSCHE, a citizen of the United States, residing at the city of St. Louis, in the State of Missouri, have 5 invented a certain new and useful Improvement in Calculating-Machines, of which the following is a full, clear, and exact description, such as will enable others skilled in the art to which it appertains to make and use the same, reference being had to the accompanying drawings, forming part of this specification, in which—

Figure 1 is a side elevational view, partly in section, of the rear end of my improved calculating-machine. Fig. 2 is a side elevational view, partly in section, of the forward end of my improved calculating-machine. Fig. 3 is a sectional view on line 3 3, Fig. 2. Fig. 4 is a top plan view of the rear end of 20 the machine. Fig. 5 is an elevational view, partly in section, of the locking devices which coöperate with the total-key. Fig. 6 is a top plan view thereof. Fig. 7 is a sectional view on line 7 7, Fig. 5. Fig. 8 is a detail view 25 showing parts of the total-key-locking mechanism in normal position. Fig. 9 is a similar view showing the total-key depressed. Fig. 10 is a similar view showing the locking mechanism for the total-key in operative position. Fig. 11 is a detail elevational view showing 30 the actuating-segment for the transferring device in its raised position ready to operate said transferring device. Fig. 12 is a similar view showing the segment locked in its elevated position. Fig. 13 is a partial side elevational view, the near wall of the casing being removed to show the interior, illustrating the connections of the driving-motor. Fig. 14 is a detail view of the clutch-disk driven 35 by the motor, and Fig. 15 is a front elevational view of the motor and its coöperating mechanism.

This invention relates to a new and useful improvement in calculating-machines, being 40 designed particularly as an improvement upon the calculating-machine patented to me July 24, 1900, No. 654,181.

The objects of this present invention are to provide devices for locking the total-key in 45 its depressed position for preventing the ele-

vation of said total-key after the operating-shaft has started its stroke. When the operating-shaft has completed its stroke, the total-key is automatically released.

Another object is to provide locking devices whereby when the operating-shaft is initially rotated the keys, while it is possible to restore them to their normal positions, cannot again be operated to place a different example on the keyboard before the completion 60 of that operation of the operating-shaft.

Another object is to provide mechanism for preventing the setting up of key-stops when the total-key is manipulated.

Another object is to print the total in a color 65 different from that of which its items are composed from a single ribbon.

Another object is to provide a lock for the segment which actuates the transferring devices for preventing a second operation of 70 the main or power shaft until the segment has completed its work.

Another object is to dispense with the use of an operating-handle, and consequently the manual labor involved in operating the 75 machine, and to provide in lieu thereof a motor having suitable connections with the operating-shaft whereby upon the depression of a key the motor is connected to the machine and makes a complete operation, said 80 motor being automatically disconnected from the machine upon the conclusion of such operation.

With these objects in view the invention consists in the arrangement, construction, 85 and combination of the several parts, all as will hereinafter be described and afterward pointed out in the claims.

The type of machine shown in the accompanying drawings is similar to that illustrated 90 and described in my former patent referred to. This machine comprises in its construction a keyboard composed of depressible keys 8, one or more of which are designed to be struck by the operator to set up an example 95 to be introduced into the machine. Upon the depression of any key of a series it is desirable that all the other keys of that series be locked against depression, as described in my said patent, the depressed key setting up 100

a stop with which coöperates slide-bars 32. These slide-bars are provided with projections at various points to coöperate with the different key-stops. In my former patent an 5 operating-handle located at the side of the machine is pulled forward, causing the slide-bars to be moved forward by friction until arrested by the stops set up by the depressed keys. In the machine of this present application this operating-handle, which is indicated in dotted lines and marked 58, may or 10 may not be used. A main shaft 57, to which the handle or other power devices are connected, is rocked in opposite directions to 15 operate the different mechanisms in the machine.

Referring now to the operation of the machine of my former patent, when the shaft 57 is rotated or rocked forwardly the slide-bars 32, which are released upon the depression of a key, are moved forward by frictional devices until the released slide-bars are arrested by the key-stops in one of nine 20 positions, depending upon the key struck. 25 When the slide-bars are forward, the main shaft 57 is rocked or rotated reversely, and mechanism is operated to cause pivoted racks 39, carried by the slide-bars, to engage the gear-wheels of the adding mechanism, which 30 engagement continues during the backward rotation of the shaft, so that in restoring the slide-bars to their normal or rearmost position the adding-wheels in mesh with the pivoted racks are rotated proportionately to the 35 forward movement of the slide-bars. There are transferring devices in the machine for operating the next adding-wheel in advance and of higher order. When the wheel of lower order is rotated the distance of ten teeth—as, 40 for instance, when the wheel operated by the units-column is moved the distance of ten teeth—the transferring mechanism will actuate the wheel in the tens-column, moving it the distance of one tooth, so that "0" will be 45 exhibited by the units-wheel and "1" by the tens-wheel. This of course is where the machine operates on the decimal system. This transferring mechanism is actuated by a segment 99, which segment when the shaft 57 50 moves the slide-bars forwardly is elevated by appropriate mechanism, and in being raised to this highest position power is stored in a spring, whereby when the segment is released the spring forces it downwardly, so that the 55 rotating shaft 97 is operated, and on this shaft are resetting-pins spirally arranged for coöperating with the trip-frames of the transferring devices. In taking a total of a sum of numbers introduced into the adding mechanism a lever designated as the "total-key" 60 is depressed, which lever effects the engagement of all of the pivoted racks on the slide-bars with the adding-wheels prior to the initial rotation of the power-shaft 57, so that upon such initial rotation of this shaft the gear-wheels are caused to rotate in what might be termed a "reverse" direction until

arrested by appropriate projections coming in contact with suitably-located stops, so that all of the adding-wheels exhibit "0" through 70 the sight-openings in the machine. It follows that the extent of movement required in advancing the gear-wheels to other than a zero position will correspond to and be identical with the extent of movement required in 75 restoring the said gear-wheels back to a zero position, and thus if any adding-wheels exhibit other than "0" through the sight-openings in the machine said adding-wheels will be rotated in a reverse direction until arrested at a point where "0" is exhibited 80 through the sight-openings. There are also printing or recording devices used in connection with the adding mechanisms, which when the shaft reaches the limit of its initial rotation will impress the condition of the machine 85 on a strip of paper. When the total-key is depressed by moving the same rearwardly to take a total and the shaft 57 is initially rotated to reversely rotate the adding mechanism, if the total-key is elevated when the power-shaft concludes its initial rotation, wherein the adding mechanism exhibits "0" 90 through the sight-openings in the machine, the pivoted racks on the slide-bars will be 95 disengaged from the adding mechanism, so that upon the final rotation of the power-shaft the slide-bars will be restored, but the adding mechanism will not be actuated. This is what is known as "clearing" the machine. 100 On the other hand, if the total-key is depressed, the power-shaft initially rotated, and the total-key held in a depressed position, so as to maintain the engagement between the pivoted racks and the adding-wheels, the 105 power-shaft in its final rotation will in restoring the slide-bars cause the pivoted racks to rotate the adding-wheels in a forward direction and cause the total to again appear 110 through the sight-openings in the machine 110 when the handle reaches its rearmost or normal position. This may be termed taking a total and keeping the total in the machine.

Referring now to Figs. 5 to 10, shaft 57 carries a quadrant 106, with which quadrant 115 coöperates a projection 111 on a lever 110, which lever is pivoted to a rock-arm 109, mounted upon a rock-shaft 50. This rock-shaft carries slotted rock-arms which coöperate with slide-bars 32, (shown in dotted lines,) 120 said slide-bars having projections which are arrested by the key-stops before referred to. 127 indicates a lever pivoted in the side frame of the machine, which frame is shown in dotted lines in Fig. 5, to which lever is connected a rock-arm 128, said arm having a slot-and-pin connection with a lever 129, pivoted inside of the side framing of the machine. This lever 129 is provided with a slot in its rear end for coöperating with the pin 130, projecting from an arm 109. In the ordinary operation of the machine—that is, when the arm 109 is moved backwardly and forwardly by the quadrant 106—pin 130 idly vibrates in 130

that portion of the slot in the rear of the arm 129 which is concentric with the axis of movement of arm 109. When lever 127 is moved rearwardly to depress the front end of lever 129, the rear end of said lever will be elevated, so as to cause the pin 130 to be located in the obliquely-arranged slot in the rear end of said lever 129, which results in moving the arm 109 forwardly, which movement effects 5 the engagement of the pivoted racks 39 with the gears 88 of the adding mechanism. The elevation of the rear end of lever 129 to accomplish the above also causes the projection 111 on the lever 110 to be raised out of the groove or slot in the periphery of the quadrant, this being done by means of a projection 131 on the lever 110, which projection extends laterally over the rear end of lever 129. (See Fig. 7.) A spring 132 exerts a pressure to 15 hold the lever 110 down at all times and to likewise hold the lever 129 depressed by reason of the lateral projection 131. This lateral projection carries guide-pins 133 on each side of the lever 129 to guide the projection 20 111 in its downward movement and cause it to reenter the slot in the quadrant. Assuming now that the total key or lever 127 is depressed, as shown in Fig. 9, it will be observed that the rear end of lever 129 is elevated, which results, as before stated, in 25 causing the engagement of the pivoted racks 39 with the gears 88 of the adding mechanism. Upon the initial movement of the power-shaft the gears 88 will be rotated reversely, assuming that they exhibit other than "0" 30 through the sight-openings in the machine, until "0" is exhibited through the sight-openings. If the lever 127 is elevated when the shaft 57 concludes its initial rotation, the arm 40 109 will be rocked, so as to cause the disengagement of the racks 39 from the gear-wheels, permitting the gears to remain stationary, exhibiting "0" through the sight-openings, while the shaft 57 makes its final movement. 45 It has been found with respect to the machine shown in my former patent that inexperienced operators will sometimes seek to obtain a total from the machine after starting to rotate the shaft 57, with the result that 50 while the total is exhibited through the sight-openings such initial movement of the shaft is sufficient to prevent a full stroke being given to the slide-bars, and consequently, as the printing mechanism is controlled directly 55 by the position of the slide-bars in printing a total, a false total will be impressed on the paper. To obviate this difficulty, I have provided mechanism for preventing the operation of the total-key after the shaft 57 has 60 been started. In addition to this I have provided means whereby should the total-key be depressed before the shaft is operated the total-key will be automatically released and be permitted to rise when the shaft concludes 65 its initial movement, so that the machine will be automatically cleared after obtaining a total from the adding mechanism. If it is de-

sired to retain the total in the machine, the operator will be compelled to hold the total-key in its depressed position. The automatic 70 clearing of the machine after obtaining a total is desirable in that inexperienced operators have after setting up an example in the machine and obtaining a total left the total-key depressed and condemn the machine, because it would no longer record examples 75 they attempted to introduce therein.

To prevent the total-key being operated after the power-shaft has been started, I arrange a track extension *a* on the quadrant 80 (see Fig. 7) and provide a pin or projection *b* on the lever 129 in advance thereof, which projection when the quadrant is moved rides over said track extension and prevents the lever 127 being operated. (See Fig. 8.) In 85 the event that the lever 127 is depressed before the power-shaft is started the projection *b* will be carried below the track extension (see Fig. 9) and the total-key will be locked 90 in its depressed position when the power-shaft is operated and until said power-shaft has completed its initial movement. This is desirable in that it insures the obtaining of the proper total and prevents inexperienced operators from depressing the total-key, starting 95 the power-shaft, and then elevating the total-key, which of course would disengage the pivoted racks from the adding-wheels before the power-shaft completes its movement, and so prevent the proper total being obtained. This track extension *a* extends such 100 a distance as to lock the total-key in its depressed position until the power-shaft concludes its initial movement, the rear end of said track extension being designated by the 105 dotted line *c*, the quadrant being shown in its extreme forward position in dotted lines in Fig. 10, wherein the projection *b* permits the lever 129 to rise, as shown by dotted lines.

To lock the total-key in its depressed position independently of the track extension before referred to, I provide a pin or projection *d* on the forward end of lever 129, which is designed to engage under a shoulder *e* of a spring-pressed lever *f*, said lever being pivotally mounted upon a shaft *g*, secured in the side framing of the machine. When the total-key is depressed and the pin *d* under the shoulder *e*, as shown in Fig. 9, it is necessary 110 to start the power-shaft for the purpose of 115 taking the total before the pin *d* on the forward end of lever 129 can be released, this release being effected by the forward edge of the quadrant contacting with a projection to disengage the shoulder *e* from the pin *d*, as 120 shown in dotted lines in Fig. 10.

It will be understood that the mechanism above described is inclosed in a casing and is inaccessible to the operator, so that when the total-key is once depressed it must be fully 125 depressed before the power-shaft can be operated, the full stroke of the total-key locking it independently of the movement of the power-shaft. When the power-shaft is start-

ed, an auxiliary lock is operated in the way of the quadrant-track, coöperating with the pin *b*. When the power-shaft concludes its initial movement, the quadrant-track releases the pin *b*, and coincidently the lever *f* is rocked to release pin *d*. The spring 132 through lever 110 depresses the rear end of lever 129 and automatically restores the total-key, (clearing the machine,) unless the total-key is held in its depressed position by the operator for the purpose of keeping the total in the machine.

In operating the machine of my former patent inexperienced operators would sometimes initially move the power-shaft 57 to add an example set up on the keyboard in the machine, after which they would operate the release-key and restore all of the keys and set up another example. They would then continue the initial movement of the power-shaft 57, with the result that neither sum set up on the keyboard would be registered in the adding mechanism. Besides, a number would be printed which would not correspond with either sum set up on the keyboard. To obviate this, I provide the shaft 57 with a projection *i*, (see Fig. 2,) which in the normal position of said shaft engages the end of a lever *j*. The opposite end of this lever *j* carries a link *k*, connected to a frame *l*, said frame being vertically movable and carrying independently-movable spring-pressed fingers *m*, which coöperate with the ends of the sliding plates 15 of the keyboard. These sliding plates 15 are common to a series of keys, and when one of the keys of a series is depressed said plate is released and moves forward. When the shaft 57 is at home, the released plate moves under its spring-pressed finger *m*. After the keys have been depressed to set up an example and the various plates 15 are in their forward position the initial movement of the power-shaft 57 will depress the frame *l* and locate the spring-pressed pins *m* in front of all the plates 15 which are not in a forward position. Those plates 15 which have been advanced will be in the path of the pins *m*, so that said pins are forced upwardly into the frame. If an operator now attempts to stop the power-shaft and restore the plates 15, he may do so; but he cannot set up another example on the keyboard, because all of the pins *m* will drop in advance of the restored plates 15 and prevent their forward movement until the power-shaft has completed its operation and been returned home, so as to raise the frame and the pins *m* out of the path of the plates 15.

It has also been found from experience that operators unfamiliar with the machine would accidentally or otherwise depress the total-key and with the total-key depressed set up an example on the keyboard and attempt to take the total at the same time that they endeavored to place a new sum in the machine. This of course would produce confusion in the results printed by the machine and ex-

hibited by the adding mechanism. To avoid this, I arrange means for restoring the plates 15 upon the depression of the total-key, whereby even if an example has been set up in the machine before the total-key is depressed the machine will be freed from said example, and when the total-key is depressed it will be impossible to place another example on the keyboard previous to a complete operation of the power-shaft 57. The plates 15 are restored manually or mechanically by a rocking frame 23, and to this frame by a slot-and-pin connection is connected a link *n*', which link is connected to a rock-arm common to the lever 134, which lever is pivoted to the inside framing of the machine and bears against the under side of a pin on the rock-arm 128. The forward end of this lever 134 carries a frame 135, whose upper cross-bar 136 extends beneath the rear ends of the fingers of the bell-crank levers 44, on which levers are arranged latch-pins 42, which in ordinary operation prevent the slide-bars 32 from moving forwardly when their friction-drivers are actuated, except when a key has been depressed, and a locking-plate 15 coöperates with the bell-crank lever to raise the latch-pin. The presence of this link *n*' does not prevent the normal operation of the restoring-frame 23; but in the event that the total-key is depressed said link positively moves said restoring-frame to restore all plates 15 and prevent the subsequent operation of said plates until the total-key is in its normal position.

In my former patent, which shows two ribbons of different colors, one for the items and the other for the totals, the item-ribbon is normally over the printing-line and all items are printed from this ribbon. The total-ribbon is designed when the total-key is operated to be placed over the printing-line, so that the total will appear in a color different from that of which its items are composed. As shown in the accompanying drawings, I do not use two independent ribbons for printing the items and the total, but employ a single ribbon or web which is made up of various colors arranged in longitudinal stripes, so that a stripe of one color will be located over the printing-line while the items are being printed, while a stripe of another color will be located over the printing-line when the total is being printed. The mechanism for operating this single ribbon of two or more colors is substantially the same as that described in my former patent, as are also the reversing devices.

It has been found that where a machine of the type illustrated in my former patent is operated by a handle time must be given to permit the segment to properly operate the transferring devices. Upon the forward movement of the handle or the initial rotation of the power-shaft the segment is lifted and power stored in its operating-spring. When the handle moves rearwardly, or the

power-shaft makes its final rotation, the spring connected to the segment forces the same down and operates the transferring devices. If the handle should be pulled forward

5 ward or the power-shaft initially rotated before the segment completes its downward stroke, some of the transferring devices might be left tripped, so that another example introduced into the machine would perhaps 10 actuate the adding-wheels and said adding-wheels would exhibit a false total, because the transferring devices had not been permitted to operate properly. Moreover, it has been the practice heretofore to require 15 operators to give an idle stroke to the operating-handle before taking a total in order to make sure that all of the transferring devices are operated and at home, so that the proper total can be taken from the machine.

20 By the presence of locking mechanism coöperating with the segment and now to be described the possibility of the machine being operated until the transferring devices are at home is obviated and the necessity for an 25 idle stroke before a total is taken is also obviated.

65 indicates the reciprocating rod, connected to and operated by the power-shaft of the machine, which rod is provided with a rack 30 at its rear end which meshes with a segment 67, fixed to a cross-shaft 68. (See Fig. 1.) This cross-shaft carries devices for preventing a return movement of the power-shaft 57 similar in all respects as shown and described 35 in my former patent referred to. Shaft 68 to all practical purposes has an initial rotation and a final rotation similar in all respects to the power-shaft 57 and corresponding 40 to what might be designated as the "forward-and-backward movement" of the operating-handle.

Referring now to Figs. 11 and 12, it will be observed that the shaft 68 carries an arm *n*, which arm is provided with a stud at one 45 end passing through a slot in a link *o*, the other end of said link being connected to a segment 99. This segment meshes with a pinion 100 of the transferring mechanism, and suitable pawls are provided, (see Fig. 1,) 50 whereby upon the upward movement of the segment (when the handle is being pulled forward) the shaft 97 is permitted to remain idle; but when said segment descends said shaft, with its carried projections, is rotated to 55 store the transferring devices. *p* indicates a spring connected to the segment 99 and in which power is stored when the segment moves upwardly. The stored energy in this spring operates to return the segment and rotate the 60 pinion 100. *q* indicates a heel on the segment which coöperates with a spring-pressed detaining-pawl *r*. This detaining-pawl *r* is operated by a pin *s*, projecting from one extremity of the arm *n*. A bell-crank lever 65 mounted upon the frame of the machine has one of its members *t* in the form of a hook or detaining-pawl for coöperating with a pin *u*

on the arm *n*, while the other of its members *v* is in the path of the segment 99 and is designed to be struck by said segment when the 70 segment is in its normal position.

Referring now to Fig. 1, where the parts are in their normal position, it will be observed that the segment is in engagement with the bell-crank lever and the hook end 75 of said lever is out of the path of the pin *u*; also, that the pin *s* is in engagement with the detaining-pawl *r*, holding the same away from the heel of the segment. The stud on the arm *n* is against the upper end wall of the slot in 80 the link *o*, so that the initial rotation of the shaft 68 will move the parts to the position shown in Fig. 11. In this position it will be noted that the arm *n* has swung around so as to release the detaining-pawl *r* and that said 85 detaining-pawl has engaged and holds the segment in a retracted position or in a position to drive the shaft 100 when the detaining-pawl *r* is operated. As the detaining-pawl *r* is controlled by the pin *s* on the arm *n*, it 90 follows that as said pin will not contact with said pawl until the parts are in the position shown in Fig. 1 the shaft 68, as well as the power-shaft 57, will have returned to their 95 normal or home positions before the segment 99 is tripped and can operate the shaft 100. Thus all of the slide-bars 32 must be restored 100 home and all of the transferring devices which are to be tripped must be tripped before the segment is released and becomes operative. The return of the shaft 68 to its home position will, as shown in Fig. 12, move the detaining-pawl *r*, so as to release the segment. The segment must now travel from the position shown in Fig. 12 to the position 105 shown in Fig. 1, or must rotate the transferring-shaft 100 one complete revolution before the segment will contact with the member *v* of the bell-crank lever and force the hook member *t* of said lever out of engagement 110 with the pin *u* on the arm *n*. Thus the shaft 68 is locked against movement while the segment is traveling from the position shown in Fig. 12 to the position shown in Fig. 1, and consequently neither the operating-handle 115 nor the power-shaft 57 can be started on another operation until the segment 99, which operates the transferring devices, has completed its work. It is of course obvious that 120 as the shaft 68 must be home before the segment is released the stud on the arm *n* offers no obstruction to the downward movement of the link through whose slot it passes. Suitable projections or pins are provided on 125 the bell-crank lever, composed of the members *t* and *v*, for arresting and limiting the movement thereof. In the event that any attempt is made to pull the operating-handle forward when the parts are in the position shown in Fig. 12 it is obvious that said handle cannot be moved on account of the lock effected 130 by the hook member *t* engaging the pin *u*. However, as soon as the segment contacts with the member *v* the hook *t* is forced out

of the path of the pin *u* and the operating-handle can be operated. It will also be noticed that the transferring devices are operated and restored by the returning-spring 5 connected to the segment. The simplicity of such an arrangement is important, as there is little liability of this single spring becoming disarranged or getting out of order; but if anything should happen to the spring or for 10 any reason the segment is locked in its upper position, as shown in Fig. 12, the machine cannot be operated, as the power-shaft is locked against rotation. In order to govern the movement of the segment, I provide a 15 dash-pot *W*, whose plunger is connected to said segment, (see Fig. 1,) and in this manner the segment is not only cushioned in its downward stroke, but the speed of movement of said downward stroke controlled.

20 Throughout the above I have referred to the power-shaft 57 and have spoken of the initial movement of said shaft corresponding to the forward movement of the operating-handle arranged thereon and of the final 25 movement of said handle as similar to the return of the operating-handle. This has been done to harmonize the description as near as possible with that contained in my former patent. I will state, however, that this present application contemplates, so far as the 30 above features are concerned, a machine whose power-shaft is operated by a manually-controlled handle or one wherein said handle is dispensed with and said power-shaft driven by a motor.

35 Referring now to Figs. 13 to 15, inclusive, I have shown a calculating-machine of the type above described, whose power-shaft 57 is provided with a segment *A* in mesh with a 40 segment *B*. A link *C* connects the segment *B* to a driven clutch-disk *D*, loosely mounted on a counter-shaft. Fixed to this counter-shaft and in juxtaposition to said disk is a 45 driven clutch member *E* in the form of a ratchet. *F* indicates a motor having a worm-gearing for driving the ratchet clutch member. In practice I prefer that this ratchet clutch member shall be constantly driven. As shown in Fig. 14, the disk *E* is provided 50 with a spring-pressed lever *G*, one end of which is designed to engage the teeth of the ratchet member of the clutch, while the other end thereof co-operates with one end of a bell-crank lever *H*, arranged in its path. This 55 bell-crank lever is held in its normal position by a suitable spring and connected by appropriate devices to a depressible key *I*, preferably arranged on the keyboard of the calculating-machine. A brake *J* in the form of a 60 yielding finger co-operates with the projection on the disk *E* for arresting said disk upon the completion of one revolution thereof when the lever *F* is thrown out of engagement with the ratchet member of the clutch. The 65 operation of this motor attachment is as follows: When an example has been set up on the keyboard, instead of reaching forward to

grasp the operating-handle to pull it forward to the limit of its movement and then release said operating-handle and waiting until it reaches its rearward or home position before setting up another example on the keyboard the operator after setting up the example simply touches the motor-key *I*. This key upon being depressed withdraws the end of 70 the bell-crank lever *H* out of the path of the lever *G*, so that the spring co-operating with said lever *G* immediately becomes effective and forces the inner end of said lever in the path of one of the ratchet-teeth of the driving member of the clutch. The instant that the inner end of the lever *G* is caught by the driving clutch member the disk *E* starts to rotate and to vibrate the segments *A* and *B*. Upon the completion of one revolution of the 75 disk *E*, if the key *I* is in its normal position, the protruding end of the lever *G* will contact with the bell-crank lever *H* to be disengaged from the driving clutch member. At the same the spring-finger *J* will contact with the projection 80 on the disk *E* and prevent momentum from carrying said disk beyond its home position. Thus it will be seen that it is only necessary for the operator to temporarily depress the key *I*, when the motor will become effective to drive 85 the machine, similar in all respects to one complete operation of the operating-handle. *K* indicates a pawl pivoted to the frame of the machine for co-operating with the shoulder on the shank of the key *I*. This pawl is 90 connected by a rod or wire *L* to a bell-crank lever *M*, pivoted at some suitable point to the framing of the machine and having one member in the path of the link *o*. This bell-crank lever is provided with a suitable spring, whereby 95 when the shaft 68 drives the link *o* upwardly the bell-crank lever is released and rises, drawing the pawl *K* against the shank of the key *I*, so that if said key *I* is elevated it cannot again be depressed while the pawl 100 is under the shoulder, or if the key is depressed the pawl will ride over the shoulder and rest thereunder when the key *I* reaches its highest position. Thus the key *I* is locked 105 against operation until the power-shaft has completed its operation. After the power-shaft has completed its operation, as has been 110 hereinbefore described, the stored energy in the segment *g* depresses said segment when it is released by the detaining-pawl *r*, and in 115 descending said segment will drive the link *o* against the bell-crank lever *M*, depressing said bell-crank lever and moving the pawl *K* from under the shoulder of the shank of the key *I*. The key *I* cannot again be operated 120 until all the parts of the machine have reached 125 a normal position. When this normal position is reached, the key *I* is released and can be again depressed to connect the motor with the power-shaft. *N* indicates a link connected to the bell-crank lever and arranged at the lower end of the key-shank, which link has a slot-and-pin connection with the segment *B*. The function of this link is to com- 130

pel the restoration of the key I when the power-shaft completes its initial rotation. This is accomplished by the engagement of the pin on the segment B with the end wall 5 of the slot in the link N when the segment B is approaching its rearmost position, and in its final rearward movement the segment B, by this link connection, positively forces the key I upwardly and restores it to its home position. An operator cannot depress the key I and hold it in a depressed position, as said key is positively forced upward to its home position and through the instrumentality of mechanism before described locked in such 10 15 home position until not only the motor has completed its work, but also until the driving mechanism for the transferring devices has completed its work.

I am aware that minor changes in the arrangement, construction, and combination of the several parts of my device can be made and substituted for those herein shown and described without in the least departing from the nature and principle of my invention.

25 Having thus described my invention, what I claim, and desire to secure by Letters Patent, is—

1. In a calculating-machine, the combination with a keyboard, of registering and recording mechanisms, a total-key, and means for locking said total-key in a depressed position to force a complete operation of the machine; substantially as described.

2. In a calculating-machine, the combination 35 40 with the keyboard, of registering and recording mechanisms, a power-shaft for driving said mechanisms, a total-key, and connections between said total-key and said power-shaft for compelling a complete operation of the latter upon the actuation of said total-key; substantially as described.

3. In a calculating-machine, the combination 45 50 with the keyboard, of registering and recording mechanisms, a power-shaft for driving said mechanisms, a total-key, and means on the power-shaft for locking the total-key in a depressed position while said shaft is rotating in one direction; substantially as described.

50 4. In a calculating-machine, the combination with the keyboard, of registering and recording mechanisms, a power-shaft for driving said mechanisms, a total-key, means for locking said total-key in its depressed position before the power-shaft is operated, and means on the power-shaft for holding the total-key in its depressed position while said power-shaft is rotating in one direction; substantially as described.

60 5. In a calculating-machine, the combination with the keyboard, of registering and recording mechanisms, a power-shaft for driving said mechanisms, a total-key, means on the power-shaft for locking said total-key when said shaft is rotating in one direction, and devices carried by said shaft for releas-

ing said total-key and permitting its restoration to a normal position; substantially as described.

6. In a calculating-machine, the combination with the registering mechanism, of sliding bars carrying racks for engaging with said mechanism, a pivoted lever for throwing said racks into and out of engagement with said registering mechanism, a total-key for operating said pivoted lever, and a power-shaft 70 75 for driving said slide-bars, said power-shaft carrying devices for locking the lever against movement after operation by the total-key; substantially as described.

7. In a calculating-machine, the combination with registering mechanism, of sliding bars carrying racks for engagement with said mechanism, a pivoted lever for throwing said racks into and out of engagement with the 80 85 registering mechanism, a power-shaft carrying means for locking said lever in either of its positions, and a hooked lever f for locking said rack-operating lever in one of its positions, said hooked lever being operated to 90 release the rack-operating lever by devices on the power-shaft; substantially as described.

8. In a calculating-machine, the combination with registering and recording mechanisms, of sliding bars carrying racks to coöperate with the registering mechanism, a power-shaft for driving said sliding bars, a total-key for throwing said racks into and out of engagement with the registering mechanism, and means on the power-shaft for coöperating 95 100 with the total-key to release the same and automatically clear the registering mechanism; substantially as described.

9. In a calculating-machine of the character described, the combination with the lever 105 129, of a total-key for operating said lever, a hooked bell-crank lever f coöperating with lever 129 in one of its positions, and a power-shaft carrying devices for coöperating with the bell-crank lever and releasing the lever 110 129; substantially as described.

10. In a calculating-machine of the character described, the combination with the lever 129 carrying a pin or projection, and a power-shaft provided with a grooved quadrant for 115 120 coöperating with said pin, whereby the lever 129 is locked against movement when in either position when the quadrant is in other than its extreme positions; substantially as described.

11. In a calculating-machine of the character described, the combination with a lever 129, of a total-key for operating the same, a bell-crank lever f for locking the lever 129 in one of its positions, a power-shaft, a grooved 125 130 quadrant on said power-shaft, and a pin or projection on the lever 129 which, in one position of said lever is in the path of the groove in the quadrant, and in another position is located above the path of travel of the quadrant, one end of the bell-crank lever f being in the path of travel of the quadrant where-

by said bell-crank lever is operated to release the lever 129 when the quadrant is in a certain position; substantially as described.

12. In a calculating-machine, the combination with the keyboard for setting up stops in different positions, of slide-bars coöperating with stops, a power-shaft for driving said slide-bars, and mechanism connected to and operated by the power-shaft for preventing the setting up of the stops by the keyboard after the power-shaft has started to make an operation; substantially as described.

13. In a calculating-machine, the combination with the keyboard for setting up stops in different positions, of slide-bars coöperating with said stops, manually-operable means for restoring the keys, a power-shaft for driving the slide-bars, and devices connected to and operated by the power-shaft for preventing the setting up of key-stops after the power-shaft has started on an operation, said devices, however, permitting the manual restoration of the key-stops; substantially as described.

14. In a calculating-machine, the combination with the keyboard for setting up stops, in which are included sliding plates 15, of slide-bars for coöperating with the key-stops, a power-shaft for driving said slide-bars, and a frame carrying yielding pins for coöperating with said sliding plates, said frames being actuated by the power-shaft; substantially as described.

15. In a calculating-machine, the combination with the keyboard for setting up stops in different positions, in which keyboard are included sliding plates 15, of slide-bars coöperating with the key-stops, a power-shaft for driving said sliding bars to and from the key-stops, a pivoted frame which is operated by said power-shaft, and spring-pressed pins m in said pivoted frame for coöperating with the sliding plates 15; substantially as described.

16. In a calculating-machine, the combination with a keyboard for setting up stops in different positions, of registering and recording mechanisms, a total-key, and devices operated by the total-key for restoring all of the key-stops; substantially as described.

17. In a calculating-machine, the combination with a keyboard, of registering and recording mechanisms, a total-key, and devices operated by said total-key for locking the keyboard against operation when the total-key is in an operative position; substantially as described.

18. In a calculating-machine, the combination with the keyboard for setting up stops in different positions, of registering and recording mechanisms, a power-shaft for operating said mechanisms, and mechanism connected to and operated by the total-key for restoring all the key-stops upon the actuation of said total-key and for preventing the setting up of any key-stop during the time that the total-key is in an operative position; substantially as described.

19. In a calculating-machine of the character described, the combination with the keyboard for setting up stops, in which keyboard are included sliding plates 15, of a rocking frame for restoring said plates, sliding bars for coöperating with the key-stops, a power-shaft for driving said sliding bars, a total-key, and mechanism connected to and operated by said total-key for releasing all of the sliding bars and restoring and locking against actuation all of the sliding plates 15; substantially as described.

20. In a calculating-machine, the combination with the registering mechanism, of a power-shaft for operating the same, transferring devices for said registering mechanism, driving mechanism for said transferring devices, which driving mechanism is initially set into position by the power-shaft, and a lock coöperating with said driving mechanism and power-shaft; substantially as described.

21. In a calculating-machine, the combination with the registering mechanism, of a power-shaft for driving the same, transferring devices, driving mechanism for said transferring devices, and a lock coöperating with said driving mechanism and with said power-shaft for locking the power-shaft against movement until the driving mechanism for the transferring devices has completed its work; substantially as described.

22. In a calculating-machine, the combination with a registering mechanism, of transferring devices coöperating therewith, a power-shaft for driving the registering mechanism, and driving mechanism for the transferring devices, which driving mechanism is set in position by the power-shaft, and power stored therein which becomes available when said driving mechanism is released, and a detaining-pawl for holding said driving mechanism in a retracted position, said detaining-pawl being tripped by devices connected to the power-shaft, which devices are operated when the power-shaft is home; substantially as described.

23. In a calculating-machine, the combination with registering and recording mechanisms, of a power-shaft for driving the same, a motor, and a clutch interposed between said motor and said power-shaft, said clutch comprising a driving ratchet member, an idle disk member, a lever pivoted on said disk member and designed to engage the ratchet member, and devices for throwing said lever into engagement with the ratchet member; substantially as described.

24. In a calculating-machine, the combination with registering and recording mechanisms, of a power-shaft for driving the same, a motor, a clutch mechanism interposed between said motor and said power-shaft, said clutch mechanism comprising a driving ratchet member, an idle disk member, a spring-pressed lever mounted on the disk member for engaging the teeth of the ratchet

driving member, means for disengaging said lever from the ratchet member, a brake for the disk member which is operated when the spring-pressed lever is out of engagement 5 with the ratchet, and a key for releasing said spring-pressed lever and permitting its engagement with the driving-ratchet; substantially as described.

25. In a calculating-machine, the combination with registering and recording mechanisms, of a power-shaft for driving the same, a motor, a clutch mechanism between said motor and said power-shaft, said clutch mechanism comprising driving and driven members, a link mounted on a crank-pin secured to the driven member, a segment to which said link is connected, and a segment on the power-shaft in mesh with said first-mentioned segment; substantially as described.

20 26. In a calculating-machine, the combination with registering and recording mechanisms, of a power-shaft for driving the same, a motor, a ratchet clutch member constantly driven by the motor, a crank-disk in juxtaposition to said member, means for engaging and disengaging said crank-disk with and from the driving ratchet clutch member, and a pitman mounted on the crank-pin of said crank-disk and coöperating with devices on 25 the power-shaft whereby, when said pitman makes a stroke, the power-shaft is partially rotated, first in one direction and then in another; substantially as described.

27. In a calculating-machine, the combination 30 with the keyboard, of registering and recording mechanisms, a power-shaft for driving said mechanisms, a motor for driving said power-shaft, a key arranged on the keyboard for throwing said motor into engagement with 35 the power-shaft, and means driven by the motor for positively restoring said key to normal position before the power-shaft is disengaged from said motor; substantially as described.

28. In a calculating-machine, the combination 40 with the keyboard, of registering and recording mechanisms, a power-shaft for driving said mechanisms, a motor which is normally disconnected from said power-shaft, a key on the keyboard for effecting the engagement 45 of the motor with the power-shaft, means for positively restoring said key to normal position before the power-shaft is disconnected from the motor, means for locking said key in its normal position, during the connection 50 between the power-shaft and motor, and means for automatically disconnecting the motor from said power-shaft after said power-shaft has made a complete operation; substantially as described.

60 29. In a calculating-machine, the combination with the registering and recording mechanisms, of a power-shaft for driving said mechanisms, a motor, a key for connecting said power-shaft with said motor, and means operated by the motor for positively restoring 65 the key to its home position before the power-

shaft is disconnected from the motor; substantially as described.

30. In a calculating-machine, the combination with the registering and recording mechanisms, of a power-shaft for driving said mechanisms, a motor, a key for connecting said power-shaft with said motor whereby the power-shaft is rocked, and mechanism for restoring said key, said mechanism being operated when the power-shaft is concluding its initial rocking movement; substantially as described.

31. In a calculating-machine, the combination with the registering and recording mechanisms, of a power-shaft for driving said mechanisms, a motor, a key for connecting said power-shaft with said motor, and means for positively restoring the key before a complete operation has been imparted to the power-shaft, said means including a link connected to the key-shank, which link has a slot-and-pin connection with one of the elements driven by the motor; substantially as described.

32. In a calculating-machine, the combination with registering and recording mechanisms, of transferring mechanism coöperating with the registering mechanism, a power-shaft for driving said mechanisms, a motor, a key for connecting said power-shaft with said 95 motor, and a lock for said key or lever which is rendered effective or ineffective by said transferring mechanism; substantially as described.

33. In a calculating-machine, the combination with registering and recording mechanisms, of transferring mechanism coöperating with the registering mechanism, a power-shaft for driving said mechanisms, a motor, a key for connecting said power-shaft with said 100 motor, and a lock for said key or lever which is thrown into an operative position whenever the transferring mechanism is in other than a normal position; substantially as described.

34. In a calculating-machine, the combination with registering and recording mechanisms, of transferring mechanism coöperating with the registering mechanism, a power-shaft for driving said mechanisms, a motor, a key for connecting said power-shaft with said 105 motor, a lock for said key or lever which is operative whenever the transferring mechanism is in other than a normal position, and means operated by said transferring mechanism when in its home position, for moving said lock into an inoperative position; substantially as described.

35. In a calculating-machine, the combination with registering and recording mechanisms, of transferring mechanism coöperating with the registering mechanism, a power-shaft for driving said mechanisms, a motor, a key for connecting said power-shaft with said 125 motor, a pawl for locking said key or lever, a rod or wire connected to said pawl, and a bell-crank lever to which said rod or wire is

connected, said bell-crank lever being in the path of movement of one of the elements of the transferring mechanism; substantially as described.

5 36. In a calculating-machine, the combination with the keyboard, of registering and recording mechanisms, a power-shaft for driving said mechanisms, a motor for operating said power-shaft, a key for rendering said 10 motor effective, means for positively restoring said key and preventing the motor from operating the power-shaft beyond the required limit, a lock coöperating with the restored key, and a transferring mechanism which is 15 operative after the motor is disconnected from said shaft, for releasing said lock; substantially as described.

37. In a calculating-machine, the combination with the keyboard, of registering and recording mechanisms, a power-shaft for driving said mechanisms, a motor for operating said power-shaft, a key for rendering said motor effective, means for positively restoring said key and preventing the motor from operating the power-shaft beyond the required limit, and means for locking said key against a second operation until the motor has completed its work; substantially as described.

38. In a calculating-machine, the combination with registering and recording mechanisms, of a power-shaft for driving the same, a motor for operating said shaft, a key, connections between said key and said motor for rendering the motor effective, means operated 30 by the motor for positively restoring the key, after operation, to its normal position, and means operated by mechanism in the calculating-machine for locking said key against a second operation until the moving parts of 40 the calculating-machine are at home, or in a normal position; substantially as described.

39. In a calculating-machine, the combination with a motor for driving the registering and recording mechanisms and storing up power in the transferring mechanism, a key 45 for rendering said motor effective, and a lock coöperating with said key, said lock being operated by the stored-up power in the transferring mechanism, after the registering and recording mechanisms have been operated by 50 the motor; substantially as described.

40. In a calculating-machine, the combination with registering and transferring mechanisms, of a motor, a key for connecting said motor with said registering mechanism to 55 drive the same and store up power in the transferring mechanism, means for positively restoring the key to normal position before the motor is disconnected from the registering mechanism, means operated by the transferring mechanism to lock the key against another operation, when so restored, until the transferring mechanism is at home, means for disconnecting the motor from the registering mechanism, means for releasing the stored- 60 up power in the transferring mechanism just before the motor is disconnected from the registering mechanism whereby, the transferring mechanism is operative after the registering mechanism has been operated by the 65 motor, and means operated by the transferring mechanism for unlocking the key when said transferring mechanism has completed its operation; substantially as described.

In testimony whereof I hereunto affix my 70 signature, in the presence of two witnesses, this 7th day of May, 1901.

FRANK C. RINSCHE.
